US00D914905S

(12) **United States Design Patent** (10) **Patent No.:** **US D914,905 S**
(45) **Date of Patent:** **** Mar. 30, 2021**

(54) **SAMPLE PROCESSING INSTRUMENT**

(71) Applicant: **LUMINEX CORPORATION**, Austin, TX (US)

(72) Inventor: **Lucas Wade**, Round Rock, TX (US)

(73) Assignee: **LUMINEX CORPORATION**, Austin, TX (US)

(**) Term: **15 Years**

(21) Appl. No.: **29/700,323**

(22) Filed: **Aug. 1, 2019**

(51) LOC (13) Cl. **24-02**

(52) U.S. Cl.

USPC **D24/216**

(58) **Field of Classification Search**

(57) **CLAIM**

The ornamental design for a sample processing instrument, as shown and described.

DESCRIPTION

FIG. 1 is a top, front, left side perspective view of a first embodiment of a sample processing instrument showing my new design;

FIG. 2 is a top, back, right side perspective view thereof;

FIG. 3 is a front elevation view thereof;

FIG. 4 is a back elevation view thereof;

FIG. 5 is a right side elevation view thereof;

FIG. 6 is a left side elevation view thereof;

FIG. 7 is a top plan view thereof;

FIG. 8 is a top, front, left side perspective view of a second embodiment of a sample processing instrument showing my new design;

FIG. 9 is a top, back, right side perspective view thereof;

FIG. 10 is a front elevation view thereof;

FIG. 11 is a back elevation view thereof;

FIG. 12 is a right side elevation view thereof;

FIG. 13 is a left side elevation view thereof; and,

FIG. 14 is a top plan view thereof.

In the drawings, the broke lines depict portions of the sample processing instrument that form no part of the claimed design.

1 Claim, 14 Drawing Sheets
